UNITED STATES PATENT OFFICE.

WILLIAM A. SPARKS AND LEO STEIN, OF HOBOKEN, NEW JERSEY.

DESIGN FOR A BASE FOR CASKETS.

SPECIFICATION forming part of Design No. 26,660, dated February 16, 1897.

Application filed September 17, 1896. Serial No. 606,183. Term of patent 7 years.

To all whom it may concern:

Be it known that we, WILLIAM A. SPARKS and LEO STEIN, of Hoboken, in the county of Hudson, in the State of New Jersey, have invented and produced a new and useful Design 5 for Caskets, of which the following is a specification, reference being had to the accompanying drawings, showing a part thereof.

Figure 1 is a top plan view of the base of a casket embodying our invention, and Fig. 2 is a side elevation thereof.

The leading feature of our design consists in a base of a casket having a substantially flat and horizontal lower edge and upwardly-projecting ends, the top edges of which ends, when viewed in top plan, as in Fig. 1, are extended in opposite directions from their central portions toward the central or intermediate portion of the base, and when viewed in elevation, as in Fig. 2, are extended or inclined upwardly in opposite directions from the central or intermediate portion of the base. The lower edge of the base is substantially flat and horizontal. The side walls of the central or intermediate portion a' of the base are substantially flat, and the opposite ends a^2 a^3 of said base project upwardly from said portion a' . The top edges a^4 of the central or intermediate portion a' are substantially parallel and horizontal, and the top edges a^5 of the upwardly-projecting ends a^2 a^3 , when viewed in top plan,

as in Fig. 1, extend in opposite directions from their central portions a^6 toward the opposite ends of the top edges a^4 , and when viewed in elevation, as in Fig. 2, the edges a^5 are extended 35 or inclined upwardly in opposite directions from the opposite ends of the edges a^4 toward the central portions a^6 of said edges a^5 . The top edges of the side walls and the upwardly-projecting ends a^2 a^3 are provided with a 40 beaded molding, and the lower portions of said side walls and ends are provided with an outwardly-flaring molding arranged substantially parallel with the lower edge of the base.

The base of a casket embodying this design 45 presents a pleasing and characteristic appearance, owing to the combined effect of the straight and curved lines and surfaces.

What we claim is—

The design for the base of a casket, substantially as herein shown and described.

In testimony whereof we have hereunto signed our names, in the presence of two attesting witnesses, at Hoboken, in the county of Hudson, in the State of New Jersey, this 55 14th day of September, 1896.

WILLIAM A. SPARKS.
LEO STEIN.
